Attorney, Agent, or Firm—Willie Krawitz

[57] **CLAIM**

The ornamental design for a stackable, polymeric container for liquids, as shown and described.

DESCRIPTION

FIG. 1 is a top plan view of a stackable, polymeric container for liquids, showing my new design;

FIG. 2 is a front elevation view thereof;

FIG. 3 is a bottom plan view thereof;

FIG. 4 is a rear elevation view thereof;

FIG. 5 is a right side elevation view thereof, and being a mirror image view of the left hand side; and,

FIG. 6 is a cross sectional view thereof, taken along lines 6—6 of FIG. 1, showing my new design.
